UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

LISTER-PLOW.

1,271,031.

Specification of Letters Patent.

Patented July 2, 1918.

Application filed January 2, 1918. Serial No. 209,917.

To all whom it may concern:

Be it known that I, WILLIAM S. GRAHAM, a citizen of the United States, and a resident of Canton, in the county of Fulton and 5 State of Illinois, have invented certain new and useful Improvements in Lister-Plows, of which the following is a specification, reference being had to the accompanying drawings.

10 This invention relates to improvements in lister-plows and has for its object to provide means capable of being readily applied to an ordinary plow of that character whereby the machine is more perfectly adapted for the operation of "double listing." By "double listing" is meant the bursting out of previously formed ridges between successive furrows that are spaced the usual distance apart, and forming in 15 place of such ridges additional furrows or trenches for the reception of additional rows of seed. Such double listing is becoming increasingly popular as its advantages are recognized. Such advantages are that 20 the ground is, of course, more thoroughly plowed; is put in better shape for cultivating; absorbs excessive moisture better; the deposited seed is not so liable to be washed out, and the roots of the plants are given 25 a better chance to extend themselves—all of which results in a larger yield. While these various advantages are quite generally recognized the operation of double listing is frequently not resorted to owing to the 30 difficulty of properly forming the additional furrows or trenches midway of adjacent furrows or trenches that have been formed the distance apart that is customary in ordinary "single listing." That the difficulty 35 is a very considerable one will be appreciated when it is borne in mind that the earth thrown upon these spaces intermediate of the first-formed set of furrows is loose, ridge-like and considerable in quantity. 40 Hence, the making of the desired furrows or trenches in such spaces necessitates skill and extreme care on the part of the operator of the machine in driving his horses, and that, too, even where one of the first-made 45 furrows is utilized, as is generally the case, as a guiding track for one of the supporting wheels of the machine to run in.

By the use of my improvements, I am able to equip an ordinary "wide-tread"

lister—as machines of the general type 55 shown in the accompanying drawings are generally termed—with means for effectively holding the plow-body in a central position with respect to the intermediate ridged strip of ground being plowed. Such 60 guiding and holding means and the manner of their adjustable and detachable connection with the machine are illustrated in the drawings and hereinafter particularly described. That which I believe to be new 65 will be pointed out in the claims.

In the drawings,—

Figure 1 is a top or plan view of a wide-tread lister plow with my improvements applied thereto;

70 Fig. 2 is a side view of the machine as shown in Fig. 1, but with one of the supporting wheels removed therefrom for the sake of clearness of illustration;

Fig. 3 is a view in perspective of one of 75 the guide-runners and the means for securing it in place upon a wheel-axle, a portion of the wheel-axle to which it is connected being shown also;

Fig. 4 is a detail, being a central vertical 80 section through the guide-runner attaching means shown in Fig. 3, and showing in elevation a portion of the guide-runner and the wheel-axle with which it is connected;

Fig. 5 is a rear view of so much of the 85 machine of Figs. 1 and 2 as is necessary to illustrate the relative positions of the parts during the double-listing operation; and

Fig. 6 is a detail of the upper end of one 90 of the links that connects a guide-runner with the plow-bail, a portion of the means for adjustably securing the link to the plow-bail being also shown.

Referring to the several figures of the drawings in which corresponding parts are 95 indicated by the same reference characters,—

10 indicates a frame member, to the side bars of which are connected the vertical legs of an arch 11. A second arch 12 is suitably 100 secured in position upon the first-named arch. The projecting end members of the arch 12 are braced to the frame by braces 13 and 14. 15 indicates a draft tongue connected to the frame of the machine, and 16 105 the driver's seat. Caster wheels 17 are provided at the rear end of the machine. 18 indicates a rock-shaft in the form of a bail

that has its horizontal end portions journaled in the side bars of the frame, to which bail is suitably attached a plow-beam 19 carrying a double mold-board plow-body 20. Connected to the plow-beam in rear of the plow-body is a seeding mechanism comprising a hopper 21 from which seed is dropped through a chute 22 into the furrow or trench made by the plow-body, the seed-dropping mechanism being operated through the rotation of the disks 23, as usual. The main supporting wheels of the machine are indicated by 24. They are journaled upon the horizontal portions of crank-axes 25. These axle members are suitably journaled in place and each is provided on its inner end with a crank portion. Through suitable means said cranks are connected with an operating lever 26, through the operation of which the supporting wheels can be given the desired relative adjustment to maintain the frame substantially horizontal when one of the supporting wheels runs in a furrow while the other runs upon unplowed ground. The means referred to, as well as the other parts, so far referred to by reference numerals, need not be here more particularly described, as by themselves they form no part of my present invention, and indeed, so far as my present invention is concerned may be quite widely varied from. For a detailed description of the construction and operation of all such parts reference is here made to Letters Patent No. 1,249,067, granted on the fourth day of December, 1917, upon an application filed by me. As in said patent, the turning of the plow-bail 18 to raise and lower the plow-body is effected through a hand-lever, here indicated by the numeral 27.

Turning now to those features which the present invention particularly relates to,—28 indicates a bracket that comprises, in the construction shown, a horizontal arm 29, a vertical arm 30, and a diagonal brace member 31 extending between said arms 29 and 30—said bracket parts being preferably formed integral with each other, as shown. Against the face of the vertical arm 30, and preferably in a shallow recess formed there-in as clearly indicated in Figs. 3 and 4, rests the upper end of a guiding device in the form of a runner 32 which is firmly held to the bracket by bolts 33 as shown, or otherwise. As shown, this runner is curved rearwardly and it is beveled as at 34 to provide a comparatively sharp or cutting edge along its lower margin, the purpose of which will be hereinafter described. There are two of these guide-runners and attaching brackets, one for each side of the machine, and each is secured in place by exactly the same means. Such means comprise a bracket 28 for attachment to one of the axle members 25 and a link for connecting the bracket to one end 65 of the plow-bail 18. Referring to the bracket connection to its axle member, it will be noted that at one end, and substantially in line with the vertical arm 30, rise two short walls 35 between which the axle member extends. These walls form a support for a block 36 that is suitably shaped to partially surround the axle and constitute a bearing therefor. The block is removably held in place by a bolt passed through one of the walls 35 as shown in Fig. 3, and also by inwardly-turned flanges at the upper ends of said walls. By removing the bolt the bearing block can be moved laterally to disengage it from the retaining walls. The upper face of the member 29 of the bracket is to be curved to fit the axle-member and thus form an extended and properly-shaped bearing between the bracket and its axle member. At the outer end of the bracket and on its under face is provided a semi-circular rib 37. 38 indicates a block properly curved to fit against the axle member 25 and located adjacent to the inner end of the bracket. This block is provided with a lateral extension or flange 38^a that is so shaped as to provide a groove or channel adapted to receive the said rib 37. 39 indicates a shackle passing over the axle member 25 and having its ends passed through opposite ends of the said block 38. By means of nuts 40 screwed tightly on the screw-threaded ends of the shackle the block 38 can be securely clamped to the axle member and, while perfectly supporting one end of the bracket in place and holding it against movement longitudinally of the axle by reason of the engagement with the rib 37, yet permit a free swing of the bracket on the axle when the guide-runner is adjusted as hereinafter described.

The bracket-attaching link hereinbefore referred to is indicated by 41. It is connected to the bracket by having its lower end turned to loosely enter a hole 42 in an ear 43 formed on the rear edge of the bracket and near the lower end thereof. From the bracket the link extends upwardly and to the rear and its upper end is screw-threaded and engaged in a screw-threaded head 44 from one face of which projects a cylindrically laterally-extending stud 45. 46 indicates a lock-nut on the link for holding it in any desired position with respect to said head 44. 47 indicates a short crank secured by a set-screw, or otherwise, to an end portion of the plow-bail 18, and through an opening in the end of the crank projects the cylindrical stud 45, it being held in place by a cotter-pin as shown in Fig. 1, or in any other suitable manner.

After a field has been plowed as in single-listing and a series of parallel furrows or trenches formed that are the usual distance apart, if it be then desired to do double-listing,—that is, form a furrow or trench between adjacent furrows or trenches that

have been formed—two runners 32 are attached by means of the brackets 28 to the respective axle members 25. They are adjusted along the axle members so as to have them equidistant from the plow-beam and so that when the plow-body is in position to plow centrally of the space between adjacent single-listing furrows or trenches they will be, respectively, but a short distance from the inner walls of the two adjacent furrows or trenches between which the double-listing furrow is made. When adjusted to proper position they are then secured there by clamping the blocks 38 to the axle members 10 as above described. The turned ends of the links 41 are then inserted respectively in the openings 42 of the ears 43,—the links having previously been adjusted as necessary with respect to the heads 44 by turning them in 15 the screw-threaded openings in such heads. The links can be placed so that their turned ends enter the eyes from either side of the ears 43,—Fig. 1 showing them entering from one side and Fig. 5 from the other side. 20 Being able to attach them in either one of these two positions facilitates adjusting the brackets along their respective axle members to bring the runners to correct position in relation to the walls of the furrows or 25 trenches. As no great range of adjustability of the runners is required owing to the quite uniform distance apart that prevails in the making of furrows or trenches in lister plowing, the adjustment that can be had by connecting the links to the brackets in one or 30 the other of these two ways is ordinarily all the provision that need be made therefor, but if a little further adjustment should be required it can be had by shifting the cranks 35 nearer to or farther from the ends of the plow-bail, as will be understood. 40

In Fig. 5 there are shown several furrows or trenches that have been formed, *a*, *a*, indicating those that have been formed in single-listing and *b*, *b*, indicating those formed in the operation of double-listing,—the plow-body 20 being in one of the latter and the runners in guiding position in two of the furrows or trenches *a*. When the 45 plow-body and the guiding devices are so located one of the supporting wheels 23 will also travel in another previously-formed furrow, thus utilizing three such furrows as guides during the making of a double-listing 50 furrow. With the parts in operative position as indicated in said Fig. 5, the runners being positioned close to the walls of the space being plowed will act not only as a guide for the central plowing of that space but will 55 act as guards to counteract any tendency of the plow to turn toward either side of such space, which tendency is ordinarily very strong, and, without such guarding means, very difficult to overcome owing to the quantity of loose dirt thrown on said space dur-

ing the making of the first series of furrows or trenches. Some of such loose dirt is almost always present also in the previously made furrows or trenches and it is, therefore, desirable to make the curved edges of 60 the runners comparatively sharp so that they may more easily pass therethrough. This sharpened edge is provided by beveling as at 34, the bevel being at that side of the runner that comes next to the wall of the 65 central space being plowed and therefore preventing the runner from readily gouging into such wall when forced against it. 70

At the end of each furrow, the plow-body will be raised of course by swinging the bail 80 18 to which the plow-beam is attached, such movement being accomplished through the lever 27. The rocking of the bail of course turns the crank-arms 47 that are fast on its ends and thereby each runner 32 is, through 85 its link 41, turned backwardly and upwardly, this being permitted through the journaling of the brackets 28 on their respective axle members 25. Thus, it will be seen, at each raising or lowering of the 90 plow-body the guiding and guarding fenders will likewise be moved automatically. 95

By my invention I provide means that can be readily and easily attached to an ordinary plow of the type mentioned without so changing or disturbing any of the parts thereof as to interfere with its working in the making of single listing furrows or 100 trenches, and that when applied will greatly lessen the labor and difficulties attendant upon double listing. While I have shown and described my invention in connection with a particular style of lister plow it is of course understood that it is capable of application to other styles or makes of lister 105 plows.

What I claim as my invention and desire to secure by Letters Patent, is—

1. In a lister-plow, the combination with a frame, axle members attached thereto, 110 wheels on said axle members, a plow-body, a rock-shaft journaled in the frame in rear of said axle members, and means for turning said shaft to raise and lower the plow-body, of a guiding device located between 115 said wheels and connected with said shaft and movable with the plow-body when said shaft is rocked, the parts being positioned relative to each other so that one of said wheels will travel in one furrow and the 120 guiding device in another furrow while the plow-body is making still another furrow.
2. In a lister-plow, the combination with a frame, axle-members attached thereto, 125 a rock-shaft journaled in the frame in rear of said axle members, with which rock-shaft the plow-body is connected, and means for turning said shaft to raise and lower the plow-body, of a guiding device pivotally 130

attached to one of said axle members and connected with said shaft so as to be movable with the plow-body when said shaft is rocked, the parts being so positioned relative to each other that one of said wheels will travel in one furrow and the guiding device in another furrow while the plow-body is making still another furrow.

3. In a lister-plow, the combination with 10 a plow-body, a rock-shaft with which said plow-body is connected, and means for turning said shaft to raise and lower the plow-body, of a guiding device connected to said shaft at each of the end portions of the 15 shaft and movable with the plow-body when said shaft is rocked, said devices being adapted to travel respectively in previously-formed furrows while the plow-body is forming another furrow between said previously-formed furrows.

4. In a lister-plow, the combination with 20 a plow-body, a rock-shaft with which said plow-body is connected, and means for turning said shaft to raise and lower the plow-body, of a crank on said shaft, a guiding device movably mounted on a suitable support at a distance from said shaft, a link connecting said crank and guiding device whereby said guiding device will be moved on its 25 support when the shaft is turned, said device being positioned to move in one furrow while the plow-body is making another furrow.

5. In a lister-plow, the combination with 30 a plow-body, a rock-shaft with which said plow-body is connected, and means for turning said shaft to raise and lower the plow-body, of a guiding device connected with said shaft and movable with the plow-body 35 when said shaft is rocked, said guiding device being adapted to travel in a previously-formed furrow while the plow-body is forming another furrow.

6. In a lister-plow, the combination with 40 a wheeled frame, a plow-body, a rock-shaft journaled in the frame, with which rock-shaft the plow-body is connected, and means for turning said shaft to raise and lower the plow-body, of a guiding device pivotally attached at its upper end to a suitable support and projecting rearwardly, and means connecting said guiding device to said rock-shaft whereby such device will be movable 45 with the plow-body when said shaft is rocked, the parts being so positioned relative to each other that one of the wheels will travel in one furrow and the guiding device in another furrow while the plow-body is making still another furrow.

7. In a lister-plow, the combination with 50 a frame, axle members thereon, supporting wheels on said axle members, a bail, and a plow-body connected therewith, of two guiding devices supported respectively on said 55 axle members at opposite sides of the longi-

tudinal center of the frame, a connection between each guiding device and the plow-bail, each of said guiding devices being positioned to run in a furrow at one side of the furrow being made by the plow-body, and 70 means for simultaneously raising and lowering the plow-body and the two guiding devices.

8. In a lister-plow, the combination with 75 a frame, axle members thereon, supporting wheels on said axle members, a bail, and a plow-body connected therewith, of two guiding devices supported respectively on said axle members at opposite sides of the longitudinal center of the frame, a connection between each guiding device and the plow-bail, each of said guiding devices being independently adjustable laterally of the frame to bring it in position to run in a furrow at one side of the furrow being made 80 by the plow-body, and means for simultaneously raising and lowering the plow-body and the two guiding devices.

9. In a lister-plow, the combination with 85 a wheeled frame, a plow-body connected therewith, and a transverse shaft supported thereby, of a bracket pivotally attached to said shaft, a plow-body guiding device attached to and depending from said bracket, said guiding device being positioned to run 90 in a furrow at one side of the furrow being made by the plow-body, a link connected to said bracket and also connected with the frame whereby said bracket is held against 95 turning on the said shaft.

10. In a lister-plow, the combination with 100 a wheeled frame, a plow-body connected therewith, and a transverse shaft supported thereby, of a bracket pivotally attached to said shaft, a plow-body guiding device attached to and depending from said bracket, said guiding device being positioned to run 105 in a furrow at one side of the furrow being made by the plow-body, a movable member carried by the frame, a link connected to said bracket and also to said movable member, means for moving the said member and link to cause a turning of the bracket, and means for locking said parts against movement.

11. In a lister-plow, the combination with 110 a wheeled frame, a plow-body connected therewith, and a transversely-arranged shaft supported thereby, of a bracket journaled upon and depending from said shaft,—said bracket comprising a horizontal arm that 115 lies parallel with the shaft, a vertical depending arm and two separated walls that partially surround the shaft for retaining a bearing block,—means on the shaft for engaging the horizontal arm of the bracket for 120 preventing movement of the bracket longitudinally of the shaft, a guiding device carried by the bracket, said bracket being positioned on the shaft to cause said guiding device to run in a furrow at one side of the 125 130

furrow being made by the plow-body, and means for rotatably holding said bracket on said shaft.

12. In a lister-plow, the combination with 15 a wheeled frame, a plow-body connected therewith, and a transversely-arranged shaft supported thereby, of a bracket journaled upon and depending from said shaft,—said bracket comprising a horizontal arm that lies 10 parallel with the shaft having near one end and on its outer face a semicircular rib and near its other end means for connecting with the shaft, and a depending arm—a block having a groove in which the rib on the horizontal arm of the bracket fits, means for 15 clamping the said block to the shaft, a plow-body guiding device carried by the bracket, said bracket being positioned on the shaft to cause said guiding device to run in a furrow at one side of the furrow being made 20 by the plow-body, and means for rotatably holding said bracket on said shaft.

13. In a lister-plow, the combination with a wheeled frame comprising two side bars 25 spaced a distance apart, of a rock-shaft hav-

ing its end portions journaled in said side bars and having a crank at one of its ends, a plow-body connected to an intermediate portion of said rock-shaft, a guiding device pivotally secured in place at its upper end and 30 located at one side of the machine so as to travel in a previously-formed furrow, a connection between said crank and said guiding device, and means for rocking said shaft to cause a simultaneous raising of the plow- 35 body and guiding device.

14. In a lister-plow, the combination with a plow-body, and a rock-shaft with which said plow-body is connected, of a guiding device pivotally secured in place at its upper end and located at one side of the machine so as to travel in a previously-formed furrow, a crank on said rock-shaft, a link 40 having a detachable connection with said guiding device and an adjustable connection 45 with said crank, and means for rocking said shaft to cause a simultaneous raising of the plow-body and guiding device.

WILLIAM S. GRAHAM.
